(57) **CLAIM**

The ornamental design for an animal training receiver, as shown and described.

DESCRIPTION

FIG. 1 is a perspective view of an animal training receiver showing the new design;

FIG. 2 is a top view of the animal training receiver of FIG. 1;

FIG. 3 is a right view of the animal training receiver of FIG. 1;

FIG. 4 is a front view of the animal training receiver of FIG. 1;

FIG. 5 is a left view of the animal training receiver of FIG. 1;

FIG. 6 is a back view of the animal training receiver of FIG. 1;

FIG. 7 is a bottom view of the animal training receiver of FIG. 1;

FIG. 8 is a perspective view of the animal training receiver depicted in conjunction with an exemplary pair of stimulus units;

FIG. 9 is a perspective view of the animal training receiver depicted in conjunction with a pair of exemplary hole protection covers;

FIG. 10 is a perspective view of the animal training receiver depicted in conjunction with an exemplary band in an unfastened state; and,

FIG. 11 is a perspective view of the animal training receiver depicted in conjunction with an exemplary band in a fastened state.

The broken line depiction of a band and stimulus input and hole protection cover components is included for illustrative purposes only and forms no part of the design claim.
